CLAIM

The ornamental design for a vital signs monitor, as shown and described.

DESCRIPTION

This vital signs monitor designed by Applicant Al Kneireim et al. is a device for making measurements of various vital signs of a human patient.

This application is related to co-pending U.S. utility patent application Ser. No. 11/032,625, entitled "A Portable Vital Signs Measurement Instrument and Method of Use Thereof", filed on even date herewith, which application is incorporated herein by reference in its entirety.

FIG. 1 is a perspective view of a vital signs monitor illustrating my new design;

FIG. 2 is a front elevation view thereof;

FIG. 3 is a left side elevation view thereof;

FIG. 4 is a right side elevation view thereof;

FIG. 5 is a top view thereof;

FIG. 6 is a bottom view thereof; and,

FIG. 7 is a rear perspective view thereof.
